W. F. KOKEN,
SHEET METAL BACK FOR BARBER CHAIRS.
APPLICATION FILED MAY 13, 1920.

1,361,387.

Patented Dec. 7, 1920.

INVENTOR

WALTER F. KOKEN,

by *Bakewell & Chase* ATTORNEYS.

UNITED STATES PATENT OFFICE.

WALTER F. KOKEN, OF ST. LOUIS, MISSOURI.

SHEET-METAL BACK FOR BARBER-CHAIRS.

1,361,387.

Specification of Letters Patent.

Patented Dec. 7, 1920.

Application filed May 13, 1920. Serial No. 381,091.

To all whom it may concern:

Be it known that I, WALTER F. KOKEN, a citizen of the United States, residing at St. Louis, Missouri, have invented a certain new and useful Improvement in Sheet-Metal Backs for Barber-Chairs, of which the following is a full, clear, and exact description, such as will enable others skilled in the art to which it appertains to make and use the same.

This invention relates to chairs of the kind that are used by barbers, dentists and other specialists, and particularly, barber chairs of the type which are provided with a metal back frame.

The metal back frame that is now generally used on barber chairs comprises a heavy casting that forms the exterior portion or exposed portion of the back frame. Metal back frames of the character referred to are exceptionally heavy and are costly to manufacture on account of the large amount of machine work required in boring holes in the casting and in grinding off the outer surface of the casting preparatory to finishing it in porcelain enamel.

The object of my invention is to provide a back frame for barber chairs, dentist chairs and the like that is light in weight, inexpensive to manufacture and of neat and ornamental appearance.

To this end I have devised a back frame for chairs of the character referred to that is composed of a core or supporting portion that carries the upholstering of the back and a sheet metal shell combined with said supporting portion so as to form the exterior or exposed portion of the back frame.

Figure 1 of the drawings is a top plan view of a back frame constructed in accordance with my invention.

Fig. 2 is an elevational view of the sheet metal shell of said frame, looking at the interior of same.

Fig. 3 is a vertical sectional view of the top cross member of the sheet metal shell and a portion of the supporting structure or core with which the shell is combined, said view being taken on the line 3-3 of Fig. 1; and

Fig. 4 is a horizontal sectional view of one of the vertical side members of the shell, taken on the line 4-4 of Fig. 1, showing a portion of the core or supporting structure.

Referring to the drawings which illus-

trate the preferred form of my invention, A designates the supporting portion or core of the back frame which preferably consists of a wooden framework either solid or of skeleton construction, and B designates the sheet metal shell that forms the exterior or exposed portion of the back frame. The shell B is preferably pressed from a single piece of sheet metal, and in the embodiment of my invention herein illustrated is in the form of a rectangular frame composed of two side members 1, a top cross member 2 and a bottom cross member 3 integrally connected together. The vertical web of the shell B is provided at its outer edge with a forwardly-projecting flange 4 that forms a rim which surrounds the supporting structure or core A and at the inner edge of said web is a small flange or bead 5 which serves to stiffen the shell and form a neat finish for the inner edge of same. The rim or forwardly-projecting flange 4 of the shell is preferably provided at its front edge with a bead or curled portion 6 that stiffens same and imparts an ornamental appearance to the back frame.

When the shell B is combined with the core or supporting structure A said shell covers the rear side of the edge portion of said supporting structure and also the top and bottom edges and the side edges of said supporting structure. The bead 5 at the inner edge of the shell laps over the upholstering material 7 that covers the rear side of the core A, and the bead 6 on the front edge of the rim 4 of the shell laps over the upholstering material 8 that covers the front side of said core, as shown in Figs. 3 and 4.

The upper cross member 2 of the shell B is preferably provided with a depending portion 9 that is pressed rearwardly at 10 so as to form a pocket in said depending portion that provides a clearance for the latch (not shown) which retains the headrest of the chair in adjusted position. The plunger or button (not shown) that is used to operate said latch projects rearwardly through a hole 11 in the rearwardly pressed portion 10 of the shell. Holes 12 are formed in the forwardly-projecting flange or rim 4 that forms the top side of the top cross member 2 of the shell so as to receive the guide rods on the headrest of the chair.

A back frame of the construction above described is light in weight, as it is composed of a lightweight supporting struc-

ture or core incased in a sheet metal shell that forms the exterior of the back frame. Such a back frame can be manufactured at a low cost, owing to the fact that the sheet metal shell of same can be pressed from a piece of sheet metal and finished in porcelain enamel without first grinding off the surface of same that is to be coated with enamel. Moreover, such a back frame presents a neat and ornamental appearance.

Having thus described my invention, what I claim as new and desire to secure by Letters Patent, is:

1. A back frame for barber chairs and the like, composed of a supporting structure or core, and a sheet metal shell combined with said supporting structure and provided with a vertically-disposed web that forms the rear side of the frame and a forwardly-projecting flange that surrounds said supporting structure and forms the exposed edge portion of the back frame.

2. A back frame for barber chairs and the like, composed of a supporting struc-

ture, and a pressed sheet metal shell combined with same and consisting of a substantially rectangular frame provided at its outer edge with a portion that surrounds said supporting structure.

3. A back frame for barber chairs and the like, comprising a sheet metal shell provided with a top cross member having a depending portion, and a pocket in said depending portion formed by pressing said portion rearwardly so as to form a depression therein.

4. A back frame for barber chairs and the like, composed of a core or supporting structure, a sheet metal shell combined with said core and provided with a vertically-disposed web that forms the rear side of the back frame and a forwardly-projecting flange or rim that surrounds the supporting structure, a depending portion on the top cross member of said shell, and a pressed part on said depending portion for the purpose described.

WALTER F. KOKEN.
